[57] CLAIM

The ornamental design for a adjustable spray nozzle for
a water hose, as shown and described.

DESCRIPTION

FIG. 1 is a perspective view of an adjustable spray
nozzle for a water hose showing my new design;

FIG. 2 is a front elevational view thereof;

FIG. 3 is a right side elevational view thereof with the
opposite side being a mirror image thereof;

FIG. 4 is a top plan view thereof;

FIG. 5 is a bottom plan view thereof; and,

FIG. 6 is a rear elevational view thereof.
